STOKER

Henry E. Lippert, Pittsburgh, Pa.

Application October 24, 1933, Serial No. 694,952

9 Claims. (Cl. 110—101)

This invention relates to stokers, and particularly to stokers of the class which transfer fuel from a source of supply and deliver it to an opening in a wall of a firebox from which opening it is scattered in aerial paths to the firebed on the grates.

In stokers of the foregoing character, it is customary to provide a throat, forwardly extending branch or mouth portion at the discharge or delivery end thereof. The direction of movement of the fuel through the stoker is usually changed at this mouth portion immediately before it is delivered to the scattering or distributing means. In practice, an indentation or recess is provided in the bottom of the mouth portion, and a distributor head is fitted within this recess to form a riffle in the mouth portion over which the fuel passes. A distributor plate, located forwardly of the distributor head, is attached to the mouth portion, in some instances, by fastening means in contact with fuel moving through the stoker. The provision of the above mentioned recess in the mouth portion necessitates machining several surfaces on the stoker part forming or containing the mouth portion and several surfaces on the distributor head, to assure a close fit of these parts and thus prevent leakage of fuel. Renewal of a distributor plate secured to the stoker by fastening means in contact with the fuel is a dirty task, since it requires removal of the fuel from a part of the stoker conduit in order that the fastening means be exposed.

Some of the objects of this invention are, to eliminate a riffle and recess in the bottom of the mouth portion, mount a distributor head exteriorly of the mouth portion upon and in contact with a single straight wall, and attach a distributor plate to the stoker adjacent the top of the mouth portion; by which construction many machining operations are eliminated, thus decreasing the cost of manufacture, and the distributor head and plate can be readily and easily assembled and dismantled for repairs and replacement, since the fastening means for these parts are accessible to facilitate the same. In accomplishing the foregoing advantages, it is another object to provide a structure wherein the distributor head extends through the distributor plate and rearward thereof, whereby pipe lines for delivering pressure fluid to the distributor head can be secured in the bottom of the head.

Other objects are, to provide a new and improved stoker fuel distributor, and provide fuel distributing apparatus having simplified means

for positively discharging fuel to the rear corners of the firebox.

On the accompanying drawings, forming a part hereof,—

Fig. 1 is a vertical longitudinal sectional view of a portion of a locomotive showing the invention applied thereto, with parts of the invention shown in elevation, 5

Fig. 2 is a horizontal section of the rear end of a locomotive and the forward end of a tender having the improved stoker in position thereon, with parts of the stoker broken away to illustrate the drive mechanism, 10

Fig. 3 is a vertical longitudinal section of the discharge end of the stoker and a portion of the locomotive backhead, 15

Fig. 4 is a horizontal sectional view taken on line 4—4 of Fig. 3, with a part of the stoker fuel distributing apparatus broken away,

Fig. 5 illustrates a modification to the discharge end of the stoker, 20

Fig. 6 is a vertical transverse section taken on line 6—6 of Fig. 3,

Fig. 7 is a vertical sectional view taken on line 7—7 of Fig. 4, 25

Fig. 8 is a sectional view taken on line 8—8 of Fig. 6, with a part broken away,

Fig. 9 is a section similar to Fig. 8 and shows modified fuel distributing apparatus,

Fig. 10 is a sectional view corresponding to Fig. 3 and illustrates an adjustable fuel directing rib in the discharge end of the stoker, 30

Fig. 11 is a horizontal section similar to Fig. 4 showing another modified form of fuel distributing apparatus, 35

Fig. 12 illustrates another modification to the discharge end of the stoker, and

Fig. 13 is a sectional view disclosing still another modified form of the stoker.

Like numerals and reference characters in the various figures on the drawings indicate corresponding elements or features of construction herein referred to. Referring particularly to Figs. 1, 2, 3, 4, 6, 7 and 8, the letter L designates a locomotive having a firebox 11 provided with grates 12, and a backhead or back wall 13 having a firing opening 14 therein. A cab 15 has a floor or deck 16 slightly below the firing opening, and a frame 17 supports the firebox and cab. A tender for the locomotive is designated by the letter T (Fig. 2). While the invention is herein shown and described as installed in a locomotive and tender, it is to be understood that its application is not limited thereto.

A horizontal conduit H, composed of a trough 55

18 and a tubular intermediate conduit section 19, communicates with and opens forwardly into the lower end of a riser conduit, indicated as a whole by the letter R, through the rear wall, 20, of the latter, the axes or centerlines of the conduits H and R being in the vertical central plane of the firing opening, the locomotive and the tender.

A portion of a water compartment, 21, of the tender is separated from the remainder thereof 10 by plates 22 to form a rectangularly shaped compartment 23 which serves to house the trough 18. The trough which may be rigidly secured to the tender in any desirable manner, opens upwardly 15 to receive fuel from a fuel bin or bunker (not shown) in the tender.

The intermediate conduit section 19 is connected at its rear end by a ball and socket joint 24 to the forward end of the trough, and its forward end is slidably mounted in a ball 25 secured 20 in a socket 26 carried by the riser conduit, whereby the intermediate conduit section can move universally with respect to both the trough and riser conduit to facilitate the flexibility between the locomotive and tender.

25 The riser conduit is arranged parallel to the backhead and secured at its upper and lower ends thereto. It comprises, generally speaking, a base casting 27, an elevator casing 28 mounted upon the base casting and extending above the cab 30 deck, and a nozzle casing or hood member 29 telescoped on the upper end of the elevator casing. The base casting 27 is substantially L-shaped forming an elbow which connects the intermediate conduit section 19 with the elevator 35 casing 28. A laterally extending arm 30 on each side of the base casting rests upon and is fixed to a bracket 31 which in turn is rigidly secured to the locomotive backhead. The base casting may be further supported upon the frame of the locomotive by means of an upright plate 32.

The riser conduit hood member 29 comprises parallel side walls 33 spaced apart a distance equal to the diameter of the elevator casing, a curved rear wall 34 connecting the side walls, an 45 L-shaped flange 35 extending outwardly from each of the side walls and having their longer legs 36 disposed in a transverse plane and their shorter legs 37 extending forwardly toward the backhead, a top wall 38 composed of a forward 50 horizontal flat section 39 and a rearward flat section 40 inclined upwardly and forwardly toward the firing opening, a lower cylindrical portion 41 having an annular recess 42 opening downwardly, and a wall 43 extending forwardly 55 from the cylindrical portion 41 and forming with the side walls 33 and the section 39 of the top wall, a mouth portion 44 opening forwardly into the lower portion of the firing opening 14. A firedoor 49 closes the upper portion of the firing 60 opening.

65 The upper end of the elevator casing is adapted to be inserted loosely within the recess 42 in the hood member. The cylindrical portion 41 is provided with a plurality of lugs 45 having threaded holes into which studs 46 are secured. These studs extend through holes in lugs 47 on the elevator casing, which holes are made to align, respectively, with the threaded holes in lugs 45. The depth of recess 42 is slightly less 70 than the distance from the top edge of the elevator casing to the lugs 47, and when the nuts 48 are turned on the studs to fasten the elevator casing to the hood member, the top edge of the elevator casing will contact with the end of the 75 recess 42, lugs 45 and 47 remaining spaced from

each other. By this arrangement it is necessary to machine only the top edge of the elevator casing and the end of the recess, and it is apparent that a tight seal against leakage of fuel into the locomotive cab can thus be made between these 5 two surfaces of relatively small area.

The top of the hood member 29 is detachable 10 to permit removal of a helical fuel transfer screw 50 from the riser conduit, when this screw is to be repaired or replaced by a new one. The 15 curved rear wall, 34, of the hood member forms an upward continuation of the rear part of the lower cylindrical portion 41; and the forward part of cylindrical portion 41 and wall 43 connect the parallel side walls 33. An angle iron 51 20 at each side of the firing opening has one leg fixed to the backhead in any desirable manner, and the other leg rigidly secured to the adjacent L-shaped flange on the hood member. The wall 43, which forms the bottom of the mouth portion, projects forward of the front faces of the transverse legs, 36, of the attachment flanges 35, and is provided with a depending relatively narrow flange 52 having a vertically disposed straight 25 front face on which a substantially bar-shaped distributor head 53 exterior of the mouth portion is mounted.

The distributor head is arranged transversely 30 of and is the same length as the width of the mouth portion 44. It consists of a top wall having an upper surface 54 arranged in a horizontal plane passing through the front top corner, 55, of the bottom of the mouth portion, a flat rear wall 56 in contact with the flange 52, a front wall 51 slightly offset rearwardly at its lower portion, 35 partition walls 58 for forming a plurality of chambers 59 in the distributor head, a bottom wall provided with bosses 60 having threaded holes or apertures opening downwardly into which pipe lines 61 are secured, and a laterally 40 projecting lug 62 on each end of the head. The pipe lines 61 correspond in number to the number of chambers in the distributor head, and serve to deliver fluid under pressure to the chambers 45 from any preferred source. Jet openings 63 are drilled in a horizontal row in the front wall, 57, of the head so that at least one jet opening will communicate with each of chambers 59. The distributor head can be secured to or removed 50 from the hood member from a position outside the firebox and in the locomotive cab, as attachment bolts 64 which extend through the projections or lugs 62 on the head also extend through the transverse legs, 36, of the flanges 35 in order 55 that nuts can be turned on the ends of these bolts which are exposed in the cab. The bolts 64 extend through flanges 35 adjacent the bottom of the mouth portion and the outer surfaces of the parallel side walls 33. By having the upper 60 surface of the distributor head lie in a horizontal plane through the front corner, 55, of the mouth portion, it is apparent that the head does not form a riffle over which the fuel passes, and since the distributor head is located exteriorly of the mouth portion it is necessary to machine only 65 one straight surface on each of the head and hood members to provide a close fit between these parts.

Extending forwardly through the firing opening from a point immediately beneath the jet 70 openings 63 is a distributor plate 65 having at the rear thereof and on each side an upstanding ear 66 containing a hole arranged to align with holes in projections 67 located on the front surface of transverse legs, 36, of flanges 35 in proximity to 75

the top of these flanges, the parallel side walls 33 and the mouth portion. A bolt at each side of the mouth portion extends through the hole in one of the ears 66 and the hole in the adjacent 5 projection 67 for hinging the distributor plate to the hood member, and the overhanging weight of the forward end of the plate causes the rear edge 68 of the plate to butt against the front wall of the distributor head. It can be understood that 10 either the distributor plate or head can be detached from the hood member without the necessity of detaching the other, and the fastening means for the plate are located so that the latter can be readily replaced from a position in the locomotive cab, merely upon opening the firedoor. A continuation, 69, of each parallel side wall 33 may be provided on the hood member to prevent fuel from falling off the sides of the head 53.

The distributor plate consists of a broad central 20 horizontal flat portion 70 having a forward part cut away allowing fuel to fall onto the firebox grates directly beneath the plate, and a depressed portion 71, at each side of the central portion, arranged to form channels which gradually increase in depth from their rear ends to their front ends and also turn laterally at their front ends. The jet openings at the ends of the row of jet openings in the head 53 are drilled to align with the channels in the plate (Fig. 4), and also 25 drilled in a manner to discharge a jet or blast of pressure fluid downwardly into the channels (Fig. 7), or stated in other words, the forwardly extended axes of the end jet openings are inclined downwardly and intersect the plane of the top 30 surface of the distributor plate, whereby fuel will positively be carried into the channels and directed laterally to the rear corners of the firebox. The distributor plate 65 is recessed at its rear end to fit around the front and sides of the 35 distributor head 53.

The top front ledge, 86, of the distributor head, over which the fuel falls onto the plate 65, is parallel to the backhead. The distributor plate and mouth portion 44 extend equal distances on 40 each side of the vertical median plane through the firing opening, and the axis of elevator screw 50 is contained in this plane.

The helical fuel transfer screw 50 extends throughout the base casting and elevator casing, 45 and a similar screw 72 is arranged within the horizontal conduit H. The upper end of screw 50 preferably terminates at a point not above the bottom wall of the mouth portion and is free of shaft bearings, and its lower end is attached to 55 a stub shaft 73 journaled in suitable bearings, including a bearing 74 integral with the base casting and extending upwardly within the same.

The fuel transfer screws are driven by a double acting two cylinder steam operated engine 75 60 mounted on the locomotive frame apart from the stoker conduit and at one side thereof, and power transmission mechanism. This mechanism comprises a short shaft 76 composed of telescopic sections one of which is universally jointed to the 65 crank shaft of the engine, gearing 77 operatively connecting shaft 76 with the front end of a relatively long shaft 78 extending from the locomotive to the rear end of trough 18 on the tender, gearing 79 operatively connecting the rear end of 70 shaft 78 with the fuel transfer screw 72, and gearing 80 operatively connecting the elevator screw 50 with the shaft 78 at a point intermediate gearing 77 and gearing 79. Gearing 80 includes a worm and a worm gear 81, the worm gear being 75 fixed on the stub shaft secured to the elevator

screw 50. The two sets of gearing 77 and 80 are enclosed in a gear box 82 attached to the underside of the base casting. Short shaft 76 is disposed longitudinally of the locomotive, and the shaft 78 extends longitudinally of both the locomotive and tender between the engine 75 and the stoker conduit. The longer shaft is composed of a center telescopic section 83 universally jointed to a rear section 84 fixed to the trough and to a forward section 85 carried by the riser conduit. 10

When the stoker is in operation, the horizontal screw 72 conveys fuel from the trough through the intermediate section 19 and discharges it forwardly onto the flight of the elevator screw 50. The fuel is elevated in the riser conduit by the elevator screw and the upwardly advancing column of fuel delivered from the upper end of the screw is flattened and directed in a mass of uniform height to the ledge 86 by the inclined section, 40, of the top wall of the hood member, 20 from which ledge it drops onto the distributor plate 65 and is discharged to all parts of the firebed by blasts of pressure fluid issuing from jet openings 63. By referring to Fig. 3 it can be understood that as the upwardly advancing fuel 25 rises in the hood member its upward movement is obstructed by the inclined wall 40 and the fuel is directed forwardly toward the distributor plate through the mouth portion 44. The frictional resistance to the movement of fuel through the 30 mouth portion on each side of the central vertical plane of the firing opening is substantially the same.

In some instances, as when the elevator screw 35 extends above the bottom wall of the mouth portion, fuel may be delivered unevenly from the upper end of the screw to the distributor plate. To remedy such a condition the top wall of the hood member may be formed or provided with a depending fuel directing rib 87 (Fig. 5) located 40 centrally of the top wall 95 to prevent more fuel being discharged to one side of the plate than the other. Fig. 10 illustrates a fuel directing rib 88 arranged in the hood member adjacent the top wall 96 thereof. The rib 88 has a shaft 97 45 pivoted centrally of and extending through the top wall. A lever 89 is attached to the rib shaft for manually adjusting the position of the rib. In Fig. 11 an adjustable fuel directing rib 90 is shown in the firing opening pivoted to the distributor plate 98 at each side of the distributor head 99. If preferred, a fuel directing rib 91 50 may be formed on the bottom wall 100 of the mouth portion centrally thereof, as illustrated in Fig. 12.

In Fig. 9 the distributor head 101 and plate 102 are shown as being constructed so that parts 92 and 93, respectively, thereof will extend exteriorly of the firebox and into the locomotive cab, whereby the head and plate can each be attached to the surface of the hood member exposed in the cab. Fig. 13 discloses a hood member 103 having a central part, 94, of the bottom wall of the mouth portion substantially narrowed, permitting the elevator casing to be located close to the backhead. 55

I claim:

1. In combination with a firebox having a firing opening, and a stoker member provided with a mouth portion in communication with 70 said opening; fuel distributing apparatus comprising a bar-shaped distributor head mounted at the bottom of the mouth portion, said head having a projection on each end thereof, means engaging said projections for attaching the head 75

to said member, the top surface of said head forming a continuation of the bottom inside surface of the mouth portion, and a distributor plate hinged to said member adjacent the top of the 5 mouth portion and having its rear edge butted against the front of said head, the front wall of said head having jet openings therein for discharging pressure fluid across said plate and being offset below the jet openings to receive the 10 rear edge of said plate.

2. In combination with a locomotive provided with a cab, a firebox having a firing opening, and a stoker fuel delivery member provided with a mouth portion in communication with the firing 15 opening; fuel distributing apparatus comprising a distributor head mounted at the bottom of said mouth portion, said head having a projection on each end thereof and a series of jet openings for the emission of pressure fluid, means for delivering 20 pressure fluid to said head, a distributor plate extending forwardly from said head and provided with an upstanding ear on its rear end at each side of the head, said series of jet openings being arranged to discharge pressure fluid 25 across said plate, and separate means for fastening the head and the plate to said member, the fastening means for the head engaging said projections and the fastening means for the plate engaging said ears, at least one of the fastening 30 means being exterior of the path of the fuel and arranged whereby the part fastened thereby can be manually attached to or removed from said member independently of the other part and from a position in the cab.

3. In combination with a firebox having a firing opening, and a stoker member provided with a mouth portion in communication with the firing opening; fuel distributing apparatus comprising a bar-shaped distributor head mounted at the 40 bottom of said mouth portion, said head having a projection on each end thereof and a series of jet openings for the emission of pressure fluid, means for delivering pressure fluid to said head, a distributor plate extending forwardly from said 45 head and provided with an upstanding ear on its rear end at each side of the head, said series of jet openings being arranged to discharge pressure fluid across said plate, and separate means for fastening the head and the plate to said member, the fastening means for the head engaging 50 said projections and the fastening means for the plate engaging said ears.

4. In combination with a firebox having a firing opening, and a stoker member provided with a mouth portion in communication with the firing opening; fuel distributing apparatus comprising a chambered bar-shaped distributor head mounted at the bottom of said mouth portion and being substantially the same length as the 60 width of the mouth portion, said head having a projection on each end thereof, a series of jet openings for the emission of pressure fluid and an aperture opening downwardly from a chamber therein for the admission of pressure fluid, 65 a distributor plate extending forwardly from said head and provided with an upstanding ear on its rear end at each side of the head, said series of jet openings being arranged to discharge pressure fluid across said plate, means 70 engaging said projections for attaching the head to said member, and means engaging said ears for attaching the plate to said member above said head.

5. In a stoker, in combination with a locomotive having a cab and a firebox having a firing 75

opening, a riser conduit provided at its upper end with a mouth portion communicating with said opening and having outwardly extending flanges for attachment of said conduit to the firebox, a distributor head at the bottom of the 5 mouth portion rigidly secured to said conduit, a distributor plate extending forwardly from said head and attached to said conduit adjacent the top of the mouth portion, said head having jet openings therein for discharging pressure 10 fluid across said plate, and separate means for fastening the head and plate to the conduit, each of the fastening means being exterior of the path 15 of the fuel and arranged whereby the head and plate can be manually secured to or removed from the conduit independently of each other and from a position in the cab, and the fastening means for the head extending through said flanges.

6. In a stoker, in combination with a firebox 20 having a firing opening, a riser conduit provided at its upper end with a mouth portion communicating with said opening, a bar-shaped distributor head mounted on said conduit at the bottom of the mouth portion, said head having a projection on each end thereof, means engaging said projections for attaching the head to said conduit, and a distributor plate hinged to said conduit and extending forwardly from said head, the front wall of said head having jet openings 30 therein for discharging pressure fluid across said plate and being offset below the jet openings to receive the rear edge of said plate, and said plate being recessed at its rear end to fit around said head. 35

7. In a stoker, in combination with a firebox having a firing opening, a riser conduit provided at its upper end with a mouth portion communicating with said opening, a bar-shaped distributor head mounted at the bottom of the mouth 40 portion and having a projection on each end thereof, means engaging said projections for attaching the head to said conduit, a distributor plate extending forwardly from said head into the firing opening, said head having jet openings 45 therein for discharging pressure fluid across said plate, an upstanding ear on the rear end of said plate at each side of the head, said plate being recessed to fit around the head and hinged to said conduit at the top of the mouth portion by 50 means engaging said ears.

8. In a stoker, in combination with a firebox having a firing opening, a riser conduit provided at its upper end with a mouth portion communicating with said opening, a bar-shaped distributor head mounted at the bottom of the mouth portion and having a projection on each end thereof, means engaging said projections for attaching said head to said conduit, a distributor plate extending forwardly from said head into 60 the firing opening, said head having jet openings therein for discharging pressure fluid across said plate, an upstanding ear on the rear end of said plate at each side of the head, said plate being recessed to fit around the head and hinged to 65 said conduit at the top of the mouth portion by means engaging said ears, whereby the overhanging weight of said plate causes its rear edge to butt against the front wall of said head and the plate is held to said front wall by its own weight. 70

9. In combination with a firebox having a firing opening, and a stoker member provided with a mouth portion in communication with the firing opening; fuel distributing apparatus comprising a distributor head mounted at the bottom 75

of said mouth portion, said head having a projection on each end thereof and a series of jet openings for the emission of pressure fluid, means for delivering pressure fluid to said head, a distributor plate extending forwardly from said head and provided with an ear on its rear end at each side of the head, said series of jet openings being arranged to discharge pressure fluid across said plate, and separate means for fastening the head

and the plate to said member whereby the head and plate can be manually secured to or removed from said member independently of each other, the fastening means for the head engaging said projections, and the fastening means for said plate engaging said ears for hinging the plate to said member. 5

HENRY E. LIPPERT.
